UNITED STATES PATENT OFFICE.

HUGH W. SANFORD, OF KNOXVILLE, TENNESSEE.

RAILWAY-CAR BRAKE.

Application filed July 18, 1921. Serial No. 485,541.

To all whom it may concern:

Be it known that I, HUGH W. SANFORD, a citizen of the United States, residing at Knoxville, in the county of Knox and State of Tennessee, have invented a new and useful Improvement in Railway-Car Brakes, of which the following is a specification, reference being had to the accompanying drawing.

10 My improvement relates particularly to brakes for mine cars and similar small cars.

The object of the invention is to simplify and reduce cost and at the same time produce an effective brake structure.

15 In the accompanying drawings,

Fig. 1 is a side elevation of a part of a mine car embodying my improvement;

Fig. 2 is an end elevation of the same car;

20 Fig. 3 is a section on the line, 3—3, of Fig. 2, looking toward the right;

Fig. 4 is a horizontal section on the line, 4—4, of Fig. 1;

25 Fig. 5 is an upright section on the line, 5—5, of Fig. 1, looking toward the left.

Referring to said drawings, A is the car body, and B B are the car wheels. C is a

30 brake strap which is long enough to be applied to both of two wheels, B, at the same side of the car. The ends, C¹, of said straps

35 are bent obliquely upward and secured to the brackets, C², which are applied to the side of the car at the left of the left hand wheel and at the right of the right hand wheel. For securing said ends, a bolt, C³,

40 extends through each end, C¹, and the adjacent bracket and also through a shim or filling washer, C⁴, placed between the bracket and the end of the strap. Any number of such washers may be introduced at either

45 end of the strap for adjusting the strap to the adjacent wheel. The face of the bracket to which the end, C¹, of the strap is applied may be regarded as the outer side or face of the bracket, because it is directed outward

50 away from the middle transverse upright plane of the car. Being thus applied, the pull of the strap is toward said outer face. And it is to be observed that while said outer face is oblique, it is also transverse to the

55 general course of the strap and the length of the car and to the horizontal plane of the car. Nearly midway between the two wheels at the right hand end of the car are placed bearings, D, each formed of a U-bolt,

D¹, and an outer plate, D², and an inner plate, D³, the outer plate being at the outer

face of the car body and the inner plate being at the inner face of said body and the U-bolt extending horizontally through said plates and said wall, the ends of the U-bolt 60 being at the inner side of said wall. On the outer face of said wall and resting in said U-bolt bearings is a rock-shaft, E. The left hand end of said shaft reaches into an upright plane midway between the two wheels 65 and is bent to form a crank, E¹, extending horizontally away from the car body and into the eye, G¹, of an upright stem, G. The lower end of said stem extends through a nut, G², a plate, G³, placed between said nut 70 and the brake strap and through the strap and through two nuts, G⁴, placed below the strap.

Turning the rock-shaft so as to move the crank, E¹, downward will cause downward 75 pressure upon the stem, G. That pressure is transmitted to the brake strap, C, through the plate, G². Thus the brake strap is forced downward on both wheels, B, B, the brackets, C², holding the ends of the strap immovably.

The engagement of the crank, E¹, in the eye, G¹, of the stem, G, is sufficiently loose to allow some movement of the lower part of the stem in the plane of the two wheels, 85 whereby automatic adjustment is made for equalizing pressure of the strap on the two wheels. Further non-automatic adjustment of the strap relative to the wheels is to be made, when needed, by the insertion or removal of washers, D⁴, between either bracket and the adjacent end of the strap, as above described. The brackets are set obliquely as shown by the drawings, in order that the face of the strap may be better engaged by 90 the bracket, and in order that the direction of the strap may be at substantially right angles to the parts of the strap approaching the brackets, whereby the adjustment of the strap by the insertion of washers, as described, is made feasible.

This simple structure, constitutes an economical and effective application of the strap to two wheels with ample adjustment for equalized pressure of the strap upon the 100 two wheels.

The rock-shaft, E, will now be further described, together with means for actuating and controlling said shaft.

From the right hand bearing, D, the rock 110 shaft, E, extends horizontally toward the right beyond the end of the car body. There

it is bent horizontally across the end of the car body and parallel to the latter to form a long arm, E^2 . Near its end, said arm is flattened to form a blade, E^3 , having a lower 5 outward-directed edge, E^4 . An approximately upright rack bar, E^5 , having teeth, E^6 , extends across the arm, E^2 , and is secured to the end of the car body by bolts, E^7 . The edge, E^4 , of the blade, E^3 , is 10 adapted to engage the teeth, E^6 , and prevent downward movement of the arm, E^2 .

The crank, E^1 , and the arm, E^2 , are at opposite sides of the axial line of the shaft, E . Hence when the arm, E^2 , is raised the crank, 15 E^1 , is moved downward, whereby the stem, G , is forced downward, and thereby the plate, G^3 , and the brake strap are forced downward. Thus the brake strap is put under tension and made to bear actively upon 20 the wheels, B , B . When the brake is to be set, the arm, E^2 , is raised manually and drawn against the teeth, E^6 , of the rack bar, E^5 , so as to make engagement between the edge, E^4 , and one of said teeth when the arm 25 reaches its upper limit. Thus the arm will be locked, and thereby the engagement of the brake strap is maintained. This engagement is intensified through the flexibility of the shaft, E , and the arm, E^2 , the shaft and 30 said arm being together of sufficient length to allow appreciable flexing, although a short section of the shaft or arm would be practically inflexible.

While provision is thus made for effectively applying the brake strap and holding it when applied, provision is also made for automatically holding the brake strap out of engagement when application is not desired. This is accomplished by placing the 35 weight of the relatively long arm, E^2 , in opposition to the crank, E^1 , and the parts supported by said crank. When the arm, E^2 , has been released from the teeth of the rack bar, E^5 , said arm, by the action of gravity 40 assumes its lowest position and by its downward movement lifts the relatively short crank, E^1 , and all the parts supported thereby, whereby the brake strap is held out of action.

To prevent the rock shaft, E , from moving leftward in the U -bolt bearings and avoiding engagement with the rack bar, E^5 , the left hand edge of the left hand U -bolt bearing plate, D^2 , is bent upward, as shown 45 in Fig. 4, so as to bear against the left hand face of the crank, E^1 , and form an abutment for the left hand side of the crank, while the right hand side of the crank bears against the adjacent U -bolt, whereby the U -bolt 50 forms an abutment to prevent rightward movement of the rock shaft.

It is now to be observed that a minimum amount of mechanism and simple movements are involved in the effective application 55 of the brake. To apply brake mecha-

nism to two wheels, one being located at one side and the other at the other side of the car, as has heretofore been done, requires mechanism that is more complex and more expensive to construct. In this connection, 70 it is to be observed that in cars of this class, the body of the car usually extends downward close to the track and precludes use of the type of brake construction used in larger railway cars having bodies high above 75 the tracks.

It is also to be observed that this structure may be produced with a limited amount of labor. No castings are needed, and no forging is needed excepting to form the rack 80 bar and the blade, E^3 , on the arm, E^2 . The rest of the work is merely cutting and punching and bending. The U -bolts are easily formed. All the nuts are ordinary stock nuts. The brackets, C^2 , are formed 85 of ordinary stock metal. It is also to be observed that the application of the various parts to the car is easily accomplished.

I claim as my invention,

1. The combination with the car body and 90 a wheel at one side of the car, of a horizontal rock shaft arranged parallel to and supported at one side of the car body and having a crank, a transverse bracket on the car body, a bolt, a brake strap attached to the outer 95 face of said bracket by said bolt and placed in operative relation with said crank to adapt said strap to be pressed into engagement with said wheel when said rock shaft is turned to move said crank downward, an 100 arm on said shaft at the side of the latter opposite the crank, whereby the weight of said arm will lift said crank and the brake means when said arm is free, and means for engaging and holding said arm when said shaft has been turned to make said engagement, substantially as described.

2. The combination with the car body and 110 a wheel at one side of the car, of a horizontal rock shaft arranged parallel to and supported at one side of the car body and having a crank, an oblique bracket on the car body, a bolt, a brake strap attached to said bracket by said bolt and placed in operative relation 115 with said crank to adapt said strap to be pressed into engagement with said wheel when said rock shaft is turned to move said crank downward, an arm on said shaft at the side of the latter opposite the crank, whereby the weight of said arm will lift said crank and the brake means when said arm is free, and means for engaging and holding said arm when said shaft has been turned to make said engagement, substantially as described.

3. The combination with a car body and 120 two wheels at one side of the car, of a horizontal rock shaft arranged parallel to and supported at one side of the car body and having a crank, two oblique brackets on the 125

car body, a bolt at each bracket, a brake strap having its ends attached to said brackets by said bolts and the strap being placed in operative relation with said crank to adapt said strap to be pressed into engagement with said two wheels when said rock shaft is turned to move said crank downward, an arm on said shaft at the side opposite the crank, whereby the weight of

said arm will lift said crank and the brake means when said arm is free and means for engaging and holding said arm when said shaft has been turned to make said engagement, substantially as described.

In testimony whereof I have signed my name, this 16th day of July, in the year one thousand nine hundred and twenty-one.

HUGH W. SANFORD.
